UNITED STATES PATENT OFFICE.

JOSEPH SALTZMAN, OF CHICAGO, ILLINOIS.

PRESSING-IRON SUPPORT.

1,191,536.

Specification of Letters Patent. Patented July 18, 1916.

Application filed June 9, 1915. Serial No. 33,063.

To all whom it may concern:

Be it known that I, JOSEPH SALTZMAN, a citizen of the United States, residing at Chicago, in the county of Cook and State of Illinois, have invented a new and useful Improvement in Pressing-Iron Supports, of which the following is a specification.

Pressing-irons commonly used by tailors and others for pressing garments or the like, are comparatively heavy and when required to be lifted from a table to operative position on the work to be pressed requires considerable expenditure of energy on the part of the operator, which has a pronounced effect upon the amount of work which an operator can complete in a given time and on the amount of energy expended by the operator.

One of my objects is to provide a novel, simple and inexpensive construction of support for a pressing-iron, by which the operator may turn out the maximum amount of work during a given time and by which the effort required to be exerted by the operator will be reduced to the minimum.

Another object is to reduce as much as possible danger of fire by contact of the iron with inflammable material; and to render unnecessary the use of a stand or pad for the iron.

Still another object is to maintain the iron, when not in use, in suspended position in such a manner that minimum exertion by the operator is required to move the iron to operative position relative to the work and still permit of the utilization of the full or substantially full weight of the iron for pressing operations.

Another object is to so support the iron that it may be readily shifted to a position in which it will in no way obstruct the operator in the use of the table in connection with which it is used, for any desired purpose, and may be readily repositioned for use in the manner as hereinbefore stated.

Referring to the accompanying drawings, Figure 1 is a view in end elevation of a pressing-table provided with a pressing-buck and equipped with a support for a pressing-iron, constructed in accordance with my invention, an iron being shown as supported thereby, but not in normal position. Fig. 2 is an enlarged broken section taken at the line 2 on Fig. 1 and viewed in the direction of the arrow. Fig. 3 is an enlarged view in elevation, partly sectional, of the free extremity

of my improved iron support. Fig. 4 is an enlarged section taken at the line 4 on Fig. 1 and viewed in the direction of the arrow. Fig. 5 is a view in end elevation of the pressing-iron of Fig. 1, showing a detail of the manner of supporting it, this view being taken from the right in Fig. 1; and Fig. 6, an enlarged view in vertical sectional elevation, of the top of the iron, showing the manner of supporting the iron from the supporting device shown in Fig. 5.

In the drawings I have shown my invention as associated with a table provided with a pressing-buck in accordance with common practice, the table being represented at 7 and the buck at 8, the latter being secured to the upper surface of the table along one edge thereof by any suitable means.

My improved iron suspending or supporting means, according to the preferred embodiment of my invention, comprises an upright supporting member 9, pivoted or swiveled to the table to rotate in a horizontal plane, a flexible member, as for example, a cable or cord 10, engaging with the support 9 and connected at one end with a pressing-iron represented at 11 and at its opposite end with spring-counterbalancing mechanism 12, the latter being so constructed as to support the iron in suspended condition.

The support 9 is preferably formed of a hollow upright section 13, a horizontally-disposed hollow section 14, and a coupling 15 connecting the adjacent ends of the sections 13 and 14 together, the sections 13 and 14, in practice, preferably being formed of gas-pipe as a matter of economy. The lower end of the section 13 extends through a bearing member 15 and into an opening 16 in the table-top in alinement with the opening in the bearing member, the bearing member 15 being secured to the table-top by bolts 17. Secured to the section 13 is a collar 18 which rests against the upper surface of the bearing member 15 and serves to hold the support 9 at the desired elevation relative to the table 7 while permitting the support 9 to be readily swung upon the bearing member 15.

The coupling 15 is preferably formed of two similar sections 19, which are clamped together at opposite sides of the members 9 and 14, through the medium of screws 20, engaging lugs 21 thereon, and shouldered

rivets 22 engaging lugs 23 thereon, the rivets 23 having journaled thereon pulleys 24, 25 and 26.

The outer end of the section 14 is provided 5 with a member 24^a, preferably formed of a tube 25 telescoping with the outer end of the member 14 and adapted to be held in adjusted position by a set-screw 26^a, and a head 27 secured to the outer end of the tube 10 25^a and carrying a pulley 28 journaled thereon.

The cable 10 extends through the sections 13 and 14, passing over the pulleys 24 and 26 under the pulley 25 and over the pulley 15 28, whereby the cord is mounted to run with the desired freedom through the support 9.

The end of the cord which passes downwardly through the section 13 of the support is connected with the upper end of the spring 12, the latter being connected with the adjustable hook device 29, adjustably mounted in a yoke 30 secured at its outer turned ends 31, as by the medium of bolts 32 25 to the underside of the table-top 7. The cable 10 may be connected with the iron 11 in any suitable manner. It is preferred, however, that the following described connection be employed. In the arrangement 30 shown, the iron 11 is connected by a ball and socket joint 33, with the lower end of an arc-shaped arm 34 having an eye 35 at its upper end, this eye engaging a link 36, which extends through an eye 37 of a turn-buckle 38, the upper end of the turn-buckle being connected with the cable 10.

Where the pressing-iron employed is heated by gas or electricity, it is preferred that the gas pipe or electric-current conducting 40 wires, as the case may be, shall be supported in a position out of the way of the operator, and this may be done by stringing them upon the support 9. In the construction illustrated, the iron 11 is shown to be 45 of the gas-heated type, the flexible pipe for conducting gas thereto being represented at 39, this pipe being threaded through eyes 40, 41 and 42, provided on the support. The eye 40 is preferably provided on a block 43 50 engaging the cable 10, the eye 41 on the outer end of the section 14 and the eyes 42 on the coupling 15, the latter eyes being clamped between the sections 19 of this coupling as illustrated in Fig. 4.

It is preferred that the spring 12 be so tensioned that the parts carried by the end 55 of the cable 10, which depends from the pulley 28, will be counterbalanced when the iron 11 occupies a vertical position in which its lower surface is below the buck 8, preferably about half way down, and practically all of the tension in the spring 12 will be 60 eliminated when the iron is raised to substantially the position represented in Fig. 1, 65 it being intended that this figure represent

substantially the position occupied by the iron when the latter is being used for pressing, and not as representing the normal condition of the apparatus.

Assuming the iron to be out of registration with the buck 8, in which condition the iron will depend at its lower edge below the top of the buck and to one side thereof, the operator grasps the handle of the iron lifting it to a position in which its lower edge 70 extends above the upper surface of the buck, and by shifting the iron laterally, moves it into position on the work placed on the buck, the support 9 swinging at its pivotal connections with the table to accommodate itself 75 to the movements of the iron. In lifting the iron as stated, the spring 12 aids in the lifting operation, but in accordance with the preferred arrangement of the parts, practically all of the tension in the spring 12 is 80 eliminated when the iron is in a plane to engage the work, and thus practically the full weight of the iron aided by pressure of the operator, if desired, may be utilized to press the work, though if desired, the tension of 85 the spring 12 may be varied. During the periods when the iron is not in use, whether while shifting the work on the buck, or substituting other work, or when other conditions prevail, the iron is pushed to one side 90 of the buck by the operator, the support 9 swinging accordingly, and upon the releasing of the iron by the operator, it descends until it reaches a position in which it becomes counterbalanced by the spring 12, it 95 being understood that in the raising or lowering of the iron, the cable 10 runs on the pulleys provided on the support.

The adjustable member 25 is desirable in that it permits of the adjustment of the device to tables of different widths, and the turn-buckle 38 permits of the adjustment of the iron relative to different heights of 100 bucks.

It will be readily understood from the 110 foregoing that by supporting a pressing-iron in accordance with my invention, the operator may use the iron with practically the same freedom as is possible where the iron is disconnected from any support, and when he wishes to position the iron out of the way, all he is required to do is to push it to one side, the support 9 rotating in this movement and the iron will hang suspended in the air out of contact with anything which 115 it might damage if allowed to rest against. While I prefer that the member 10 be a cable, it will be readily understood that any other suitable flexible member may be substituted, it being my intention by the use 120 of the word "cable" in the appended claims, to include any other suitable flexible member.

While I have illustrated and described 125 a particular embodiment of my invention, 130

I do not wish to be understood as limiting it thereto, as the same may be variously modified and altered without departing from the spirit of the invention.

5 What I claim as new and desire to secure by Letters Patent is—

1. In apparatus of the character set forth, the combination of a base, an upright support on said base provided with a laterally-extending arm adapted to be adjusted to cause its outer extremity to extend closer to or farther away from said upright, a cable 10 engaging and supported by said support and engaging the outer extremity of said arm, adapted to move lengthwise of said support and arm, a pressing-iron connected with the end of said cable adjacent to the outer end of said arm, and counterbalancing means connected with the other end of 15 said cable.

2. In a device of the character set forth, the combination of a table, an upright hollow member journaled thereon to swing about a vertical axis, a hollow substantially 20 horizontally-disposed member, means coupling the adjacent ends of said upright and said horizontal member together, pulleys supported adjacent said coupling, a pulley supported at the outer end of said horizontal member and adjustable toward and away from said upright, a cable extending through said upright and horizontal member and engaging said pulleys, a pressing-iron connected with the end of said cable 25 which depends from the pulley at the outer end of said horizontal member, and a spring engaging at one end with said table and at its other end with the other end of said cable.

30 3. In apparatus of the character set forth, the combination of a table, a base secured

thereon, an upright member pivoted to said base to swing about a vertical axis and provided with a laterally-extending arm, a cable supported by said upright member and 45 arm, and adapted to be moved longitudinally thereof and engaging the outer end of said arm, a pressing-iron connected with the end of said cable adjacent the outer end of said arm, the opposite end of said cable extending below the top of said table, 50 a bracket secured to said table and extending below its top, and a spring connected with said bracket and with the last-referred to end of said cable. 55

4. In a device of the character described, the combination of a table, an upright hollow member journaled thereon to swing about a vertical axis, a hollow substantially 60 horizontally-disposed member, means coupling the adjacent ends of said upright and said horizontal member together, said means comprising clamp members applied to opposite sides of said upright and said horizontally-disposed member, and means clamping them in position, pulleys and means on said clamp members for journaling said pulleys thereon, a pulley supported adjacent the outer end of said horizontally-disposed member, a cable extending through said upright and said last-referred-to member and engaging said pulleys, a pressing-iron connected with the end of said cable which depends from the pulley at the outer end of 65 said horizontal member, and a spring engaging at one end with said table and at its other end with the other end of said cable. 70 75

JOSEPH SALTZMAN.
